UNITED STATES PATENT OFFICE.

DAVID THOM SCOTT, OF VANCOUVER, BRITISH COLUMBIA, CANADA.

INTERNAL-COMBUSTION ENGINE.

Application filed April 5, 1927, Serial No. 181,218, and in Canada September 18, 1926.

My invention relates to improvements in internal combustion engines having for its objects the provision of means whereby opposed pistons may be utilized in a single cylinder without having recourse to the use of an endwise movable sleeve; to provide a pair of connecting rods for the upper piston which are of sufficient length to reduce side thrust upon the wrist pins thereof; to permit of adequate cooling of the pistons through their direct contact with the cylinder walls and to provide a construction whereby an engine of the type having opposed pistons in a single cylinder may be of relatively short vertical length.

The invention consists essentially of an engine base having a crank shaft, a cylinder upon the base, and opposed pistons endwise movable therein having rod connection to the crank shaft, as will be more fully described in the following specification, in which:—

Fig. 1 is a longitudinal sectional view of the engine showing the pistons at the point of firing.

Fig. 2 is a transverse sectional view showing the pistons at the outer ends of their strokes.

Fig. 3 is a plan view in section showing the radiating fins on the upper piston head.

In the drawings like characters of reference indicate corresponding parts in each figure.

The numeral 1 indicates generally a crank case having crank shaft bearings 2 and a top wall 3 from which a sleeve or cylinder extension 4 depends to form an additional guide to the lower piston. The top wall 3 is provided with a pair of slotted openings 5.

The numeral 6 indicates generally a water jacketed open ended cylinder having an annular passage 7 adjacent its upper end provided with upper and lower ports numbered 8 and 9 respectively, through which the partially compressed charge of air or combustible mixture is adapted to flow at predetermined intervals.

The numeral 10 indicates a threaded aperture which is adapted to be fitted with a spark plug if the engine is to be run with gasoline or light fuels, or a firing plug if heavy oils are to be used.

The numeral 11 indicates a plurality of ports (shown in dotted lines in Figure 1) which communicate with an exhaust pipe or manifold 12.

The numeral 13 indicates an intake head of larger diameter than the cylinder 6, which is adapted to extend downwards over the cylinder 6 and to be mounted on a flange 14 thereon, see Figure 2, and is provided with a pair of opposed vertical slots 15 within which the wrist pins of the upper piston are adapted to move. The intake head is provided with detachable cover 16 having an internal projection 17 designed to reduce the cubic capacity of the head, so as to obtain a desired compression of the air to be admitted to the working space between the opposed pistons.

The numeral 18 indicates a plurality of ports communicating with an inlet pipe 19 which may be fitted with a poppet valve if the fuel is to be admitted with the air. The numeral 20 indicates a crank shaft having a centre crank pin 21 and a pair of side crank pins 22 which are set at an angle of 180 degrees from the crank pin 21.

The numeral 23 indicates a piston of the ordinary internal combustion engine type having a wrist pin 24 and a connecting rod 25 mounted at its big end to the crank pin 21.

The numeral 26 indicates generally a piston slidably movable in the upper end of the cylinder 6 and the head 13 and is formed with a sleeve portion 27 having a piston head 28 adjacent its lower end, which is provided with fins 29 on its upper surface which are adapted to dissipate some of the heat of the firing charge into the air or vapour admitted to the engine as it flows from the head through a plurality of ports 30 in the sleeve portion 27 through the ports 8, the annular passage 7 and the ports 9 into the firing space of the cylinder 6. The lower extremity of the sleeve portion 27 extends beyond the piston head 28 to form a portion of the required compression space of the cylinder and is provided with rings 31 in the usual manner. The upper extremity of the sleeve is provided with an annular flange 32, the purpose of which will hereinafter appear.

The numeral 33 indicates an outer sleeve of such internal diameter to pass freely over the outer walls of the cylinder 6 and is provided at its lower end with a pair of trunnions 34 which are secured thereto by any suitable means, and are fitted with a pair of connecting rods 35, the big ends of which are connected to the crank pins 22. The upper end of the outer sleeve is fitted on its ex-

ternal periphery with piston rings 36 which form a gas tight connection with the inner walls of the head 13. The upper end of the outer sleeve is also provided with an internal annular flange 37 for the purpose of forming a seat to which the flange 32 of the upper piston 26 is secured.

I may prefer to fit an intake bye pass 38 extending from the inlet pipe 19 or on the engine side of the inlet valve, if such should be fitted, and leading upwards through a suitable check valve 39 to a port 40 communicating with the upper extremity of the head 13 so that as the piston 26 descends air or mixture is drawn into the head 13 through the port 40 in such reasonable quantity as to reduce the negative pressure that would otherwise be developed by the down-stroke of the piston before the ports 18 would be opened.

Having thus described the several parts of my invention I will now briefly explain its cycle when operated as a two stroke engine having its charge admitted in the form of combustible gas and fired by a spark plug.

The upper piston 26 on descending past the intake ports 18 allows an inrush of combustible gas to the head 13, on the upstroke of the same piston this charge is lightly compressed between the piston head 28 and the cover 16 until the ports 30 of the sleeve portion 27 of the piston 26 register with the ports 8 of the cylinder 6 when the lightly compressed gas passes through the ports 8, the annular passage 7 and the ports 9 around the lower extremity of the piston and into the firing space of the cylinder, this flood of gas fills the firing space and in its downward flow causes the residue of the prior spent charge to be ejected through the exhaust ports 11. On the return or approaching movement of the pistons viz: the down-stroke of the upper piston 26 and the up-stroke of the lower piston 23, exhaust ports 11 and the inlet ports 9 are closed off and the gas is compressed between the opposing piston heads, when by a suitable timing

mechanism it is ignited by the spark plug fitted into the aperture 10 of the cylinder 6, thus consuming and expanding the charge and driving the pistons in opposite directions away from each other and imparting rotation to the crank shaft 20 through the connecting rods 35 and 25. The final downward movement of the piston 23 uncovers the ports 11 to allow the spent gases to escape from the cylinder.

What I claim as my invention is:

1. A two stroke internal combustion engine comprising a suitably journalled crank shaft having opposed crank pins, an open ended cylinder having a lower piston, rod connected to one of the crank pins, an intake head upon the cylinder, an upper piston having a head adjacent its lower extremity and being endwise movable and in operative engagement with the cylinder and the intake head, said piston rod being connected to the other crank pin, said piston head having radiating fins projecting upwardly into the intake head, means for bye-passing the mixture admitted to the intake head into the cylinder between the pistons, means for igniting the same and for exhausting the products of combustion from the cylinder.

2. In a two stroke internal combustion engine having a crank shaft, opposed crank pins operatively connected to lower and upper pistons endwise movable within a cylinder, an intake head upon the cylinder having ports communicating with an intake pipe adapted to be closed by the upper piston during the major portion of its upward and downward movement, and a bye pass tube extending from the intake pipe having a check valve and being in communication with a port adjacent the upper end of the intake head, means for transferring the mixture from the intake head to the cylinder between the pistons, and means for igniting the same and for exhausting the products of combustion from the cylinder.

Dated at Vancouver, B. C., this 14th day of March, 1927.

DAVID THOM SCOTT.
